UNITED STATES PATENT OFFICE.

EDWIN B. CRAM, OF BROOKLYN, NEW YORK, ASSIGNOR TO NEW YORK ADDING TYPE-WRITER COMPANY, OF ORANGE, NEW JERSEY, A CORPORATION OF MISSOURI.

TYPE-BAR-OPERATING MECHANISM.

988,979.

Specification of Letters Patent. Patented Apr. 11, 1911.

Application filed January 11, 1904. Serial No. 188,555.

To all whom it may concern:

Be it known that I, EDWIN B. CRAM, a citizen of the United States, residing at Brooklyn, Kings county, State of New York, have invented certain new and useful Improvements in Type-Bar-Operating Mechanism, of which the following is a specification.

This invention relates to improvements in mechanism for operating the type-bars of typewriting machines, the object of the invention being to reduce binding and torsional strain on the type-bar and its operating devices.

15 The invention will be fully described hereinafter, reference being had to the accompanying drawings in which:—

Figure 1 is a plan view partly broken away of so much of a typewriter as is necessary to illustrate my invention; Fig. 2 is a vertical longitudinal section; Fig. 3 is a plan view showing a type-bar and connections detached; Fig. 4 is a detail view of a guide roller and supporting bracket; Fig. 5 is a 25 detail view partly in section of a type-bar hanger and a portion of a type-bar; Fig. 6 is a perspective view of a connecting bar, detached; and Fig. 7 is a plan view of a hanger-securing cap-plate.

20 The machine frame A is suitably constructed to support upper and lower arc plates 276 and 295 upon which is mounted the typewriter mechanism, and also a paper carriage (not shown) carrying the usual cylindrical platen P. The typewriting mechanism comprises a plurality of type-bars 392 arranged in suitable relation to the platen P, each bar being hung in a hanger O secured to the lower arc-plate, and oper-
35 atively connected to a vertically movable key bar 271 which is connected with a numeral key I or a lettered key 35 according as the type-bar to which it is connected bears a numeral or a letter type. The type-bars 40 have the usual type heads and are arranged in well known relation to the platen the hangers being arranged about the lower arc plate as shown in Fig. 1. Each hanger consists of two similar side plates 322 which are 45 connected together and spaced apart by rivets 288, each rivet having shoulders which bear against the inner surfaces of the plates and hold them the required distance apart to receive a hub 320 of a type-bar without 50 undue friction. A pivot pin 294 is prefer-

ably tightly fitted in the hub and its ends are tapered to have a working fit in tapered holes in the plates 322. This hanger is not of my invention and I lay no claim thereto. To secure the hangers firmly in position a cap-plate 321 is laid upon their tops and firmly secured to the arc plate 295. Each type-bar is connected to one of the reciprocating bars 271 by means of a connecting rod 291 pivoted to the type-bar at 293 and to a lug 277 upon the bar 271. The connecting rods 291 are U-shaped in cross section and the lug 277 extends between the sides thereof and is pivoted thereto. At each end the back of the connecting bar is cut away thereby forming forked ends to permit the type-bar 392 and connecting bar 291 to swing freely.

The bars 271 are of rectangular cross section and at a plurality of points as at the upper and lower ends, each works between a pair of guide rollers 273 having rectangular peripheral grooves into which the edges of the bar extend and these rollers are substantially alike at both ends of the bar. Each pair of rollers is supported in a bracket having the sides 275 at right angles to the bottom and each side has an open top recess 279 the opposing ends of which form bearings for the journals 274 of the rollers, and overhanging lips 314 prevent upward movement of the rollers. The parts are so formed and proportioned that when the rollers are in place and engage the bar 271 the latter will have a running fit between them and be guided thereby in its movement and the bar will hold the roller journals in place beneath the lips. The upper brackets are secured to the upper arc plate 276 and the lower ones to the lower arc plate 295 and each bracket has a hole cut in its bottom for the passage of a bar 271 and the arc plates are provided with holes for the same purpose. Each lug 277 is formed by making two transverse cuts in the bar 271, extending from the center of the bar to its rear edge and extending the metal between the cuts beyond the rear edge of the bar.

The radial distances from the guide bars 271 to the points of connection of the rods 291 to the type-bars 392 vary, and depend upon the positions of the type bar hangers, which hangers are not arranged in an arc of a circle as are the guide bars 271. I have found that best results are obtained when

this condition is met by varying the lengths of the lugs 277 and maintaining the length of the connecting rods 291 uniform. This variation in length of lugs is shown clearly in Fig. 1. The points of connection of the lugs 277 and connecting rods 291 are not all located on arcs of a circle concentric with the printing point but are arranged on arcs of different circles neither of which is concentric with the printing point. The reason for this arrangement is that by it the pivotal points of the type bars are concentrated or brought relatively close together thus economizing space and providing for combining an adding mechanism with the type-writing devices. Another reason for making the lugs 277 of different lengths, rather than varying the lengths of the connecting rods 291, is that if the latter plan was followed the extent of depression of the outer rows of keys, in order to bring the type to printing position, would have to be considerably greater than the extent of depression of the keys nearer the center of the key board. This would be objectionable to the operator and would also render it practically impossible to employ the mechanism in a combined typewriting and adding machine, for which the present invention is particularly adapted.

Referring to Fig. 7, it will be seen that the type bar hangers are arranged on a curved line formed by the arcs of three circles $a'-a'$, $b'-b'$, and $c'-c'$ having the centers a , b , c , respectively, neither of said centers being coincident with the printing point indicated at p . As stated above the guide bars 271 are arranged in the arc of a circle and as the type bar hangers are not arranged on the arc of a circle it will be seen that the pivotal points of the type bars adjacent the ends of the series will be at greater distances from said guide bars 271 than will the corresponding points of the intermediate type bars. And, consequently, as before stated, the distances between the points of connection of the rods 291 with the type bars and the guide bars 271 will not be uniform throughout the series. In order that all of the connecting rods 291 may be of uniform length, the lugs 277 of the guide bars 271 toward the ends of the series gradually increase in length as shown in Fig. 1.

Secured to the bars 271 are L-shaped arms 300 which pass downwardly through guide slots 306 in a plate 304 secured to the lower arc plate, the rear edges of the arms engaging the bottoms of the slots. The arms then extend horizontally to the front of the machine where they support the stems of the keys 1 and 35. Preferably the key stems are round in cross section. The holes in the key board through which the stems pass are elongated lengthwise of the machine so as to permit forward and backward play of the

stems, but the sides of the holes bear against the stems laterally to guide the stem and prevent binding of the mechanism. To each arm is connected a lifting spring 310 which is also connected to the upper arc plate.

Inasmuch as the flat blades constituting the key bars are not upon the same vertical plane as that in which the type bars swing, but are each in a plane at an angle to that of the type bar, the lugs 277 of the key bars are bent each to one side at an angle to the plane of its key bar, as best illustrated in Figs. 1 and 3, so that the pivotal points 293, 233 are parallel to each other in the same vertical plane and there is no tendency to destroy this parallelism, which would result in causing friction and binding and interfere with the free action of the parts. Inasmuch as any back thrust in the direction of the longitudinal line of each of the connecting bars 291, Fig. 3, is at an angle to the vertical plane of the key bar 271, there would be a tendency to twist the latter or swing it upon its longitudinal vertical center if means were not provided to prevent any such action, and such means consists of the upper and lower sets of guide rolls with grooves coinciding with the shape of the flat or angular key bar and which prevent any such twisting or turning of the body of the bar whatever its vertical plane.

No claim is herein made to the particular construction of hanger and manner of connecting the type-bar thereto, which is herein illustrated, as the same is the invention of W. H. Pike, Jr., and forms the subject-matter of Letters-Patent No. 813,364 dated February 27, 1906.

Without limiting myself to the precise details of construction illustrated and described, I claim:—

1. The combination with a type bar, of a flat key bar set in a vertical plane at an angle to that of the type bar, an intermediate connecting rod, and upper and lower guide rolls for the key bar having grooves conforming to the form of said key bar for the purpose set forth.

2. The combination with a type bar of a key bar angular in cross section set in a vertical plane at an angle to that of the type bar, an intermediate connecting rod, and upper and lower guide rolls for the key bar having grooves conforming to the form of said key bar for the purpose set forth.

3. The combination with the key bar of a typewriter, of upper and lower guides, a key and its stem, and an L-shaped arm, the vertical portion connected at one side to the key bar and extending below the lower guides thereof, and the horizontal portion extended forward and connected with the lower end of the key stem.

4. In a typewriting machine the combination of a plurality of key bars each having a

laterally projecting lug bent to one side, guides engaging each bar above and below the lug thereof, type bars pivoted at their lower ends, and connecting rods each pivoted at its lower end to one of the type bars and at its outer end to one of said lugs.

5. In a typewriting machine, the combination of a plurality of concentrically arranged key bars having lugs of different 10 lengths, a plurality of pivoted type bars having their pivots positioned at different distances from the key bars and arranged to strike at a common point, and connecting rods of uniform length connecting the 15 bars with said lugs on the key bars.

6. In a typewriting machine, the combination with the key bar and connected key, of a bracket having parallel sides at right angles to its bottom, each side having an open top recess with over-hanging lips at each end of the recess, and a pair of grooved

rollers having journals engaging the ends of the recesses below the over-hanging lips and between which rollers the bar is guided, substantially as described.

7. In a typewriting machine, the combination of a plurality of vertically movable key bars, each having at one edge a laterally extending lug, each lug being separated from the body of its bar by incisions extending to the axis of said bar, and said lugs being of different lengths, type bars, and rods each pivotally connected to a type bar and the lug of one of the key bars, said connecting rods being of uniform length.

In testimony whereof I have signed my name to this specification in the presence of two subscribing witnesses.

EDWIN B. CRAM.
